Des. 215,802
Patented Nov. 4, 1969

215,802

TOOTH CLEANING DEVICE

Carroll C. Conklin, Jr., 722 S. Prospect St.,
Marion, Ohio 43302

Filed Sept. 12, 1968, Ser. No. 13,515

Term of patent 14 years

Int. Cl. D4—02; D24—03

U.S. Cl. D4—24

FIG. 1

FIG. 2

FIG. 3

FIG. 4

FIG. 1 is a top plan view of a tooth cleaning device showing my new design;

FIG. 2 is a side elevation thereof;

FIG. 3 is an end elevation thereof; and

FIG. 4 is a bottom plan view thereof.

I claim:

The ornamental design for a tooth cleaning device, as shown.
